E. BRIGGS & G. G. CARPENTER.
MOWING, THRASHING, AND CLEANING GRAIN.

Patented Feb. 5, 1836.

Feb 5, 1836

A. Franklin Briggs and George G. Carpenter of Franklin Co. N.Y.
Letters Patent

The Schedule referred to in these Letters Patent and making part of the same containing a description in the words of the said A. Franklin Briggs and George G. Carpenter themselves of their improvement in the machine for Harvesting, Threshing and Cleaning Grain.

To all to whom these Presents shall come: Be it known that A. Franklin Briggs and George G. Carpenter, of Fort Covington in the County of Franklin and State of New York, have invented a new and useful improvement in Harvesting, Threshing and Cleaning Grain, and that the following is, in full and exact description of the construction and operation of said machine as invented by us. The machine may be erected upon four wheels, like the four wheels of a wagon, and the team harnessed to it as to a wagon. The fore wheel has a pair of hind wheels ten feet long, they are nine feet apart and connected by a single one foot wide and fourteen feet long, with a flat angle iron framed to its right two feet from it, but eleven feet long. At the right are two scythes six feet long, and four feet apart attached to an arbor parallel with, and six feet from, the hind wheel, by arms winding them thirty two and a half degrees as they revolve to and from a crank connected to the scythe arm, will meet a quadrant on the parallel arbor, and press the two scythes between the scythes forward of their edges to let the cut grain slide down from it on to the first feed or, enclosing two arbor, three feet long and six inches, stop parallel with the scythes above by timbers framed to the scythe and hind arbor. Said first feeder will run parallel with the scythes, and at right angles, and convey the grain on to a second feeder of like fashion, but running backwards, six feet convey the grain off between the stalks, into the threshing wheel, which is two feet long, and one in diameter. Directly back

Feb 5, 1836

of this is a cylinder two feet long and an equal diameter having teeth to separate the straw from the grain and these end on it a concave of half inch spaces, point bars set to an angle of forty five degrees, under the fore end of this is a cylinder one foot in diameter with an aperture in its back and inside a fan to blow the chaff as the grain falls through the concave into a large bin. To the right hand wheel hub attach a cogged wheel two feet in diameter geared to a six inch wheel on the hub of a low neck pulley with a belt enclose this with an eight inch pulley on the sighthouse bar join to the low neck an eighteen inch pulley enclosed with a band around the inner foot roll. enclose also the eighteen inch with a band around a six inch pulley on the separator, which is joined to a twenty inch pulley by a band around a three inch pulley on the fan. But when expedient let there be instead of the above described sighthouse first feed a beam reaching from the hub of the three foot forward, and one upward, applied to the fore end of this a beam four feet long parallel with the walkway two and a half feet below this frame. To it a like beam be tween these two pendent beams put two upright cylinders eighteen inches in diameter and two feet apart, enclose these with a belt two and a half feet wide, having in it eight upright rods, to each rod four fingers and a eighth each one foot long the lower ends of said rods make an angle from the sighthouse backward eight inches and run in a groove between the faces of the cylinders to keep the sighthouse and giving it right angles with the belt while cutting and conveying the grain on to the feeder of the thresher. These upright cylinders may be geared to the right hand wheel by two pairs of broad cogged wheels connected by an arbor three feet long. Attach to the left hand wheel hub a cogged wheel, two feet in diameter geared to an eight inch wheel on an arbor ten inches long placed on the neck and on a plank five feet long

Feb 5, 1836

joined to the rear, and a wheel two and a half feet in diameter is joined to the right inch and geared to a seven inch wheel on the arbor of a two foot wheel ground to a six inch wheel on the arbor of the threshing; the arbor of the two foot wheel rests ten inches above the sides of the threshing on posts, and on it is a nine inch pulley, around which is a band encircling the hand feed roll.

As when the machine is moved forward, the left hand wheel following is at the back of the left front wheel, the whole of which receiving its propelling power from the team that moves it.

He claims especially the manner and principles of applying the power of a team, to cutting, threshing, and cleaning grain, by moving forward the machine, of cutting grain, of conveying it to the threshing, of threshing and of cleaning grain, by processes applied.

I declare that the foregoing is a true and correct description of my said invention. We have hereunto set our hands in Fort Covington aforesaid on the twenty-ninth day of October in the year of our Lord one thousand Eighteen hundred and thirty six.
